UNITED STATES PATENT OFFICE.

AUGUSTO BONTEMPI, OF NEW YORK, N. Y., ASSIGNOR OF ONE-HALF TO
ILLIAN VON GEISSNER, OF NEW YORK, N. Y.

TYPE-WRITING MACHINE.

No. 825,261.

Specification of Letters Patent.

Patented July 3, 1906.

Application filed March 13, 1905. Serial No. 249,957.

To all whom it may concern:

Be it known that I, AUGUSTO BONTEMPI, a subject of the King of Italy, residing in the city of New York, State of New York, have 5 invented certain new and useful Improvements in Type-Writing Machines, of which the following is a specification.

This invention relates to type-writing machines, and more particularly to that class 10 employed for writing in books.

It has for its object to provide a machine in which the platen is arranged perpendicular to the line of writing and the printing mechanism travels relatively to the keyboard in 15 the direction of line-spacing.

The invention further embodies improvements in platens, paper-clamps, printing mechanisms, inking mechanisms, letter-spacing mechanisms, and line-spacing mechan- 20 isms.

Other and further objects will appear in the following description and will be more particularly pointed out in the appended claims.

25 In the drawings, Figure 1 is a perspective view of my invention. Fig. 2 is a section on the line 2 2, Fig. 3, showing the platen and type-carrier in elevation. Fig. 3 is a top plan view of the keyboard mechanism with the front casing removed. Fig. 4 is a front elevation of the keyboard mechanism with the front casing removed, parts being broken away. Fig. 5 is a detail view of one of the paper-clamps. Fig. 6 is a vertical transverse 30 sectional view through the printing mechanism with the type-carriers removed. Fig. 7 is a section on the line 7 7, Fig. 6. Fig. 8 is a plan view of the inking-pads, showing the mounting thereof. Fig. 9 is a section of one 35 of the type-carriers. Figs. 10 and 11 are respectively bottom and side views of the third and first type-carriers. Fig. 12 is a central longitudinal vertical section of the printing mechanism. Figs. 13, 14, and 15 are detail 40 views of the platen-return mechanism, the alarm, and the scale. Fig. 16 is a detail view of the mechanism for throwing the different lines of type to the printing-line. Fig. 17 is a detail of the platen-feed mechanism. Fig. 18 45 is a detail view of the line-spacing mechanism. Figs. 19 and 20 are detail views of the hammer-operating mechanism.

Referring more particularly to the drawings, 1 indicates a base-plate, enlarged at its

forward end at 2, an upright 3 extending from 55 the rear of the enlargement, and an upright 4 extending from the rear of the base-plate. Spaced above the base-plate 1 and journaled in the uprights 3 and 4 is a roller-platen 5, which extends transversely of the printing- 60 line.

Paper or work clamps.—Also journaled in the uprights 3 and 4 is a pair of parallel oscillatory shafts 6 and 7, operated in a manner to be hereinafter described. Slidably mounted 65 on these shafts is a pair of work or paper clamps, one for the top and one for the bottom of the leaf of a book or for a sheet of paper. The clamps (see Fig. 5) are composed of a frame 8, which slides on the bars 6 and 7 70 and carries near its lower end a roller 9. A vertically-movable frame 10, having a key 11 at its upper end and yoked at its lower end, slides on the frame 8 and is for this purpose provided with a slot 12, in which works the 75 shaft of the roller 9. The lower end of the frame 10 carries rollers 13, each of which is adapted to be disposed on one side of the platen 5. Passing around the rollers 13 and the roller 9 is an endless elastic band 14, 80 which bears under tension on the platen 5 between the rollers 13 when the rollers 13 are lowered, thereby holding the paper to the platen and permitting its feed in the direction of the line of writing. The frame 10 is 85 notched at 15 and has a sidewise movement in the frame 8, so that the tooth 16 on the frame 8 may be thrown in the notches 15 by spring 10^a to hold the frame 10 at various positions and consequently increase or decrease the pressure on the paper.

Printing mechanism.—The printing mechanism comprises three cases of type, each containing twenty-eight characters. The first case embodies all the small letters of the 95 alphabet, the second the capital letters, and the third the numerals and various signs, accents, &c., each case being mounted in a separate type-carrier 17 17^a 17^b. Each type-carrier (see Figs. 9, 10, and 11) has two rows of 100 sliding parallel types 18, which are non-circular in cross-section to prevent their turning and are held in elevated or raised positions by coiled springs 19. The type-carriers are provided with openings 20, one 105 above each type, and on their sides they are provided with grooves 21. The three type-carriers are mounted on a carrier-support 22,

(see Figs. 6 and 12,) side by side, and are adapted for movement in the direction transverse to the axis of the platen, this movement being permitted by the grooves 21, in which work the guides 23 on the support 22. Depending from the front and back of the carrier-support 22 are guide-arms 22^a, in which work the ends of two oppositely-disposed U-shaped frames 22^b, each of which 10 embraces one end of the series of type-carriers and under the action of spiral springs 22^c serve to normally hold the type-carriers in alinement. The carrier-support 22 is supported by means of guides 24 from a printing-mechanism carrier. The printing-mechanism carrier (see Figs. 2, 6, 7, and 12) comprises a fixed sleeve 26 and an oscillatory sleeve 27, connected so as to travel together. The oscillatory or cam sleeve 27 is provided 20 with a cam or helicoidal groove 29, in which works a projection 30 on the top of carrier-support 22, and when the sleeve 27 is turned by a means hereinafter described the type-carrier support, together with the type-carriers, is caused to move longitudinally of the platen relatively to the printing-mechanism carrier. Extending upwardly from the carrier is an upright 31, having a cross-bar 32, which connects a pair of sleeves 32^a, sliding 30 on the oscillatory shafts 6 and 7, before mentioned. The shafts 6 and 7 are longitudinally grooved at 6^a 7^a, while the sleeves are provided with feathers 33, which cause the sleeves to oscillate with the shafts, but permitting them to move axially relatively thereto. Each sleeve 32^a has extending therefrom a type-carrier-positioning arm 34^a 34^b, one being positioned at each end of the type-carriers in a position to strike and move the type-carrier located over the printing-point. Also mounted by means of lateral perforated arms 35 on the upright 31 is a sliding hammer-pin 36, held in a raised position over the printing-point by means of coiled spring 37. This 40 hammer-pin is adapted to be struck by the tappet-arm 38 on a sleeve 39. The sleeve 39 is carried by a shaft 40; which is located to one side of and below the shaft 7 and is longitudinally grooved at 41 to permit a feather 42 on the interior of the sleeve 39 to travel longitudinally of the shaft, but to cause the sleeve to turn with the hammer-shaft. The sleeve 39 is provided with an annular groove 43, in which a lug 44 on the fixed sleeve 26 50 projects and causes the tappet-arm to travel with the printing mechanism.

Line-spacing.—The printing mechanism is caused to travel relatively to the keyboard in a direction transverse to the printing-line 60 by means of a screw-shaft 45, which extends through sleeve 26, the sleeve 26 having an internal projection 46, which takes into the threads of the screw-shaft 45. The forward end of the screw-shaft, which is journaled in the upright 3, (see Fig. 18,) is provided with a

toothed wheel 47. Adjacent the toothed wheel is mounted on the upright 3 a slide-bar 48, provided with a key 49 at its upper end and carrying a yielding rack 50, which when the bar 48 is depressed is thrown into engagement with the toothed wheel 47, causing the rotation of the screw-shaft 45 and a consequent advancement of the printing mechanism. The slide-bar is returned to an elevated or normal position by a coiled spring 51 and in returning the rack 50 being pivoted at 52 rides freely over the toothed wheel 47. To secure a variable line-spacing, the pin 53, which limits the downward movement of the slide-bar 48 and together with the pin 54 acts as a guide therefor, is adjustable in the openings 55.

Positioning type over printing-point.—The cam-sleeve 27, which determines the line of type of the type-carriers to be positioned over the printing-line, has extending therethrough a shaft 56, which has a longitudinal groove 57, in which a lug 58 on the interior of sleeve 27 works. The groove and the key permit the sleeve to move axially on the shaft, but to turn therewith. As the cam-sleeve 27 has connection with the carrier-support 22 by means of the helicoidal or cam groove 29 and the projection 30, the shaft 56 in oscillating causes the carrier-support 22 to be shifted and one of the lines of types other than the first (which is normally over the printing-line) to be shifted to the printing-line. The shaft 56, which causes the movement, is journaled in the uprights 3 and 4 and at its forward end, on the rear side of the upright 3, is provided with a pinion 59, with which meshes a segmental rack 60 on the end of a bell-crank lever 61. The bell-crank lever 61 (see Figs. 2, 3, 4, and 16) is pivoted at the juncture of its two arms to the rear of upright 3 at 61^a and at its lower end is provided with a curved cross-piece 62, provided with three lugs 63^a, 63^b, and 63^c. Also pivoted at 61^a is a pair of levers 72 and 73 for controlling, respectively, the second case or capitals and the third case or numerals, accents, &c. The two levers 72 and 73 are respectively provided at one end with keys 74 and 75 and have their movements limited by lugs 76 and 77. Both levers have the same throw, but their free ends 78 and 79 are located different distances from a lug 80 on the bell-crank lever 61, so that when they are depressed they will move the bell-crank lever different distances, owing to one of them engaging the bell-crank lever before the other, thereby causing the shaft 56 to be oscillated to different positions and throwing different cases into printing position, where they may be engaged by the type-carrier-positioning arms 34^a and 34^b. As before stated, the front line of the first case is normally over the printing-line, and when either of the keys 74 or 75 is depressed the front line of its case is

thrown to the printing-line. To obtain the upper line of any case, there is located below the cross-piece 62 an inclined or beveled end 64 of an upwardly-extending arm 65 on a lever 66. The lever 66 is pivoted at 67 on the rear side of upright 3 and carries at its other end a lateral arm 68, which extends through a slot 69 in the upright and beneath a universal bar 70 of U-shaped form pivoted on pivot-bars 71^a and 71^b on the front face of the upright 3. The universal bar 70 is provided with a series of depressions or notches 81, which serve to permit certain of the key-levers 82, corresponding to the type of the first line of each case, to move without operating the universal bar, while the other key-levers rest against the bar 70. Upon every depression of the bar it depresses one end of the lever 66, elevates the beveled end 64 of the arm 65 into engagement with one of the lugs 63^a 63^b 63^c, (depending upon which case is in position,) and causes the case in printing position to be moved so that the second line of type is over the printing-line.

The key-levers 82 (see Figs. 2, 3, and 4) are pivoted on the pivot-bars 71^a and 71^b, one-half, or fourteen, on each bar. Each has extending upwardly from its rear end an arm 83, carrying at its upper end a head 84, curved on an arc having for its center the pivot-bars 71^a 71^b. These heads 84 of each key-lever group are of different sizes, so as to be located different distances from the swinging plates 85^a 85^b, one of which is common to each group of key-levers. The swinging plates are journaled at 86 on horizontal axes and have extending therefrom arms 87, carrying lateral pins 88. Each of these pins 88 engages with a crank-arm 89 on the shafts 6 or 7. It will thus be seen that on every depression of a key-lever the arm 83 thereof engages one of the plates 85^a or 85^b, swinging the same and causing the rocking or oscillation of one of the shafts 6 or 7, which in turn swings one of the type-carrier-positioning arms to engage the type-carrier positioned over the printing-point and move it transversely of the axis of the platen a distance depending upon the key operated, the distance being determined by the distance of the head 84 from the plate 85^a or 85^b.

Hammer-operating mechanism.—After the swinging plate 85^a or 85^b has moved the required distance the curved portion of the head 84 passes beneath the lower edge thereof and holds the same in proper position while the tappet-arm 38 is operated. This is accomplished by means of a second universal bar 90 (see Figs. 4, 19, and 20) of U shape swung from the pivot-bars 71^a and 71^b. This universal bar extends under all the key-levers 82 and is moved by all of them. It has depending from it a curved arm 91, which near the end of the movements of the key-levers engages with an arm 92 of a bell-

crank lever pivoted at 93 to the front face of the upright 3. The upper arm 94 of this bell-crank lever is provided with a pin 95, working in a slot 96 in an arm 97 on the hammer-shaft 40. Thus the hammer-shaft 70 is rotated, causing the movement of the tappet-arm 38, which forces the hammer-pin 36 against the upper end of the type that is disposed above the printing-point. So that the force of the blow of the tappet-arm may be varied, the universal bar 90 is provided on one or both of its arms with a depending lug 98, and the upright 3 has passing through it an adjusting-screw 99, adapted to be struck by the lug 98 to limit the downward movement 80 of the universal bar 90.

Platen-feed.—Upon the front end of the roller-platen 5 are mounted a large inner pinion 100 and a smaller outer pinion 101, with which mesh, respectively, a small pinion 102 85 and a large pinion 103, which are mounted on a fixed shaft 104, located above the platen-pinions on the front face of the upright. Housed within the large pinion 103 is a platen-return spring 105, one end of the spring 90 being secured to the pinion 103 and the other end being secured to shaft 104. Turning with the pinions 102 and 103 is a disk 106, provided with an annular series of numbered pin-openings 108, forming the scale. Within 95 these pin-openings is adapted to be fitted a pin 109 to provide an adjustable marginal stop, the pin engaging with a fixed projection 110 on the frame. A bell 111 also turns with pinions 102 103 and disk 106, and a spring-pressed striker therein engages with the projection 110 on the frame when the end of a line is reached. Below the pinions 100 and 101 is mounted a pinion 112, which carries an escapement-wheel 113. The escapement-wheel 113 is controlled by a dog 114, which is pivoted at its lower end at 115 and at its upper end carries a yielding tooth 116 and a fixed tooth 117, the yielding tooth being normally held in the path of the teeth on 110 the escapement-wheel by means of a spring 118. Every time that the universal bar 90 is depressed a depending cam-arm 119 engages with a cam extension 120 on the dog 114, and moves the dog so that the yielding tooth 116 is out of the plane of the escapement-wheel, while the fixed tooth is thrown into the plane thereof to prevent its movement. When the yielding tooth moves out of the path of the escapement-wheel, it rises 120 slightly under the action of its spring 116^a, and when the universal bar 90 is released the dog 114 moves to normal position, and the yielding tooth 116 is in a position in advance of the tooth of the escapement which it before engaged. The escapement-wheel under the action of the spring 105 is now advanced, the tooth 116 yielding to permit an advance a distance equal to the space between two letters. If it is desired to quickly feed the 130

sheet from one side to the other, both teeth of the dog 114 are thrown out of the path of the escapement. This is accomplished by means of a key-lever 117, which connects with the dog 114 and which when depressed causes this result.

Reversing-platen.—To move the platen 5 in a reverse direction, two means are employed. In one the platen is moved back only one space, this being accomplished by a key-lever 118^a, the end 119^a of which is normally out of the path of the escapement-wheel; but when the key-lever is depressed it is elevated and engages one of the teeth of the escapement-wheel and moves it back one space. This back feed is advantageous for corrections and accent-marks. The other means for reversing the feed comprises a sliding rack-bar 120, having a key 121 at its upper end and positioned on the upright 3, so that it will engage with pinion 102 and pinion 112. It is obvious that if the rack-bar 120 is depressed the platen will be returned to normal position.

Inking mechanism.—The type are inked by means of a plate 122, carrying inking-pads 123^a 123^b. The plate is bifurcated at its rear end and is pivoted at 124 to a depending portion 125 of the printing-mechanism carrier, being held normally up against the printing-face of the type in the type-carriers by a leaf-spring 124^a. The front and rear type-carriers 17 and 17^b are provided with beveled lugs 126 and 127. When the printing-pads 123^a 123^b are against the face of the type, these beveled lugs rest in openings 128 and 129, through the latter of which the type are projected, it being disposed over the printing-point. When the type-carrier support 22 is moved longitudinally of the axis of the platen 5 to dispose any line of type (other than the first line of the first carrier) over the printing-line, the lug 126 rides out of opening 128 and into longitudinal pathway 130 between the inking-pads, thereby depressing the plate 122 away from the face of the type and permitting the movement of the carriers. If the type to be used is in the first line of the first carrier or the last line of the last carrier, neither of the lugs 126 nor 127 would be in pathway 130, and for this reason a lateral pathway 131 is provided, so that a depression of the pads away from the type will take place.

General operation.—A book is fitted below the platen 5, as seen in Fig. 5, with the center of the binding to one side of the platen. A leaf is then passed over the platen between the platen and the work-clamp. This may be done by turning the knob 132, carried by the bell, depressing key 121, or elevating the work-clamps and feeding the sheet through by hand. If either of the first two methods is employed, power is stored up in return-spring 105. The printing mechanism is moved to the rear of the machine by

turning shaft 45 or by exerting a rearward pressure on the printing mechanism. The lower line of type of the lower case is then disposed over the printing-line and the writing is started. Upon the striking of every character-key the printing mechanism is first shifted to place the proper line over the printing-line, then it is shifted by arms 34^a or 34^b to place the proper type over the printing-point. When the proper type is in position, the tappet-arm 38 hits hammer 36 and an impression is made. About this time the depressed key is released, whereupon the printing mechanism returns to normal position and the platen with the sheet is fed forward one space. The space between words is obtained by striking key *F w d*, which is pivoted on pivot-bars 71^a and 71^b and bears on universal bar 90. A back space is obtained by striking key 118^a. When the end of a line is reached, key 121 is depressed to return the platen and the paper to positions to start a line and key 49 is depressed to move the printing mechanism toward the front of the machine the space of one line. This operation is continued until the writing upon the sheet has been completed.

While I have shown and described an embodiment of my invention, I desire it to be understood that within the scope of the appended claims I may make various changes without departing from the spirit or sacrificing any of the advantages of my invention.

What I claim, and desire to secure by Letters Patent, is—

1. In a type-writing machine, a keyboard, a printing mechanism movable for line-spacing transverse to the printing-line and relatively to the keyboard, and a platen movable in the direction of the printing-line for letter-spacing.
2. In a type-writing machine, a keyboard, a printing mechanism movable for line-spacing transverse to the printing-line and relatively to the keyboard, and a roller-platen movable in the direction of the printing-line for letter-spacing.
3. In a type-writing machine a keyboard, a platen rotatable on an axis transverse of the printing-line for letter-spacing, and a printing mechanism movable relatively to the keyboard and to the platen, transverse of the printing-line and in the direction of the axis of the platen for line-spacing.
4. In a type-writing machine, the combination with the keyboard, of the platen movable relatively to the keyboard in the direction of letter-spacing, a printing mechanism movable relatively to the keyboard in the direction of line-spacing, and a screw-shaft for causing the movement of the printing mechanism.
5. The combination with the stationary keyboard, of a roller-platen extending rearwardly from the keyboard, and a printing

mechanism movable longitudinally of the axis of the platen and relatively to the keyboard for line-spacing.

6. The combination with the frame of a horizontal roller-platen spaced above the frame, a keyboard from which the frame and the platen extend rearwardly, and a printing mechanism movable over the platen longitudinally of the axis of the platen, and relatively to the keyboard.

7. The combination with platen rotatable to produce letter-spacing, a rotatable bell mounted on the frame of the machine, a reducing-gear interposed between the bell and the platen, and a striker engaging the bell when the end of the line is reached.

8. In a type-writing machine, a printing mechanism embodying a plurality of rows of type arranged in parallel lines, each pair of lines representing a different case, means for first throwing one of the lines of each case over the printing-line, and means for throwing the other line of each case to the printing-line constructed to operate only after the first line of the case has been thrown to the printing-line.

9. In a type-writing machine, a printing mechanism embodying a plurality of rows of type arranged in parallel lines, the lines being divided into groups representing different cases each case embodying a plurality of lines or rows; means for throwing one line of any one of the cases to printing position, a keyboard having its keys divided into a plurality of groups each containing a plurality of keys, and connections between one group of the keys and the printing mechanism for throwing to printing position the other lines of the case at printing position constructed to operate only after the first line of the case has been thrown to the printing-line.

10. In a type-writing machine, a printing mechanism embodying a plurality of rows of type arranged in parallel lines, the rows being divided into groups representing different cases, means for moving one of the lines of one of the cases to the printing-line, and means for moving the case in printing position, in the direction of the line of printing independently of the other cases to dispose one of its type over the printing-point.

11. In a type-writing machine, a printing mechanism embodying a plurality of rows of type arranged in parallel lines, the rows being divided into groups representing different cases each case embodying a plurality of lines or rows, means for throwing one line of any one of the cases to the printing-line, a keyboard having its keys divided into a plurality of groups each containing a plurality of keys, connections between one group of the keys and the printing mechanism for moving in the direction of the printing-line, the line over the printing-line, to dispose the proper

type over the printing-point, and connection between another group of the keys and the printing mechanism constructed to cause another line of the same case to be first thrown to the printing-line and then moved in the direction of the printing-line only after one line of the case has been thrown to the printing-line.

12. In a type-writing machine, a printing mechanism embodying a plurality of type-carriers each having two rows of type thereon, a keyboard having its keys divided into two groups each containing a plurality of keys, a bar operated by one group of the keys of said board, means for throwing one row of any one of the carriers to the printing-line, and connection between the type-carriers and the key-operated bar constructed to throw to the printing-line the other line of the carrier which is in printing position only after one row of type of a carrier has been thrown to the printing-line.

13. In a type-writing machine, a printing mechanism embodying a plurality of rows of type arranged in parallel lines, the rows being divided into pairs each representing different cases, a rotary helicoidal grooved device, a shaft on which said device is mounted, a pinion on said shaft, a bell-crank carrying a segment at one end meshing with the pinion and a curved cross-piece at the other end carrying projections, a pivoted lever beveled at one end and positioned adjacent the curved cross-piece of the bell-crank, a keyboard, a bar adapted to be thrown into engagement with the other end of the pivoted lever when certain of the keys of the keyboard are operated, and means for disposing any one of the lugs on the cross-piece over the beveled end of the lever so that when the keys which operate the bar are depressed, the beveled end of the pivoted lever will engage one of the lugs and cause the rotation of the helicoidal device and a movement of the rows of type.

14. The combination with a shaft, of a helicoidal sleeve adapted to move longitudinally thereof but to turn therewith, a printing mechanism having a plurality of parallel rows of type, and means for rotating the shaft to throw any row of type over the printing-line.

15. The combination of the printing-mechanism carrier, a shaft for advancing the same transverse of the printing-line, a type-carrier carried by the printing-mechanism carrier and having parallel rows of type thereon, a second shaft, means for oscillating the same, a sleeve adapted to travel with the printing-mechanism carrier on the second shaft and to turn therewith, connections between the sleeve and the type-carrier to cause the movement of the type-carrier transverse of the printing-line and relatively to the printing-mechanism carrier when the second shaft is

rotated, a third shaft, and means traveling on the third shaft and with the printing-mechanism carrier and adapted, when the third shaft is oscillated, to cause the movement of the type-carrier in the direction of the printing-line.

16. In a type-writing machine, mechanism comprising a plurality of type-carriers having parallel rows of type thereon, the carriers being movable together transverse of the printing-line to dispose the proper line over the printing-line and the carrier in printing position being movable in the direction of the printing-line independently of the other to dispose the proper type over the printing-point.

17. In a type-writing machine, a plurality of type-carriers having a plurality of parallel rows of type, means moving the carriers together transversely of the printing-line to dispose the proper row over the printing-line and oscillatory arms mounted on opposite sides of the type-carriers and adapted to move the type-carrier that is in printing position, in different directions longitudinally of the printing-line.

18. In a type-writing machine, a type-carrier having a row of type thereon and oscillatory arms disposed at opposite ends of the carrier to move the same in opposite directions.

19. In a type-writing machine, a type-carrier having a plurality of rows of type thereon and movable in the direction of the line of printing and transversely thereto, a plurality of keys having connection with the type-carrier to move it only in the direction of the line of printing, and a plurality of keys having connection with the type-carrier to move it transversely of the line of printing and also in the direction of the line of printing.

20. The combination with the platen movable in the direction of the line of writing, of a stationary keyboard, a printing mechanism, and a feed-screw for moving the printing mechanism transversely of the line of printing and relatively to the keyboard.

21. The combination with the platen movable in the direction of the line of printing, of a stationary keyboard, a type-carrier, a feed-screw for moving the type-carrier transverse of the line of printing, and connections between the keyboard and the type-carrier for shifting any type of the type-carrier to printing-point.

22. The combination with the printing mechanism, of a hammer-shaft, a sleeve carrying a tappet-arm to cause the impression of the type disposed over the printing-point, said sleeve turning with the hammer-shaft but movable axially thereof, a slotted arm on the hammer-shaft, a pivoted bell-crank lever engaging at one end in the slotted arm, a universal bar adapted for engagement with the other end of the bell-crank lever, and the

key-levers adapted for engagement with the universal bar.

23. The combination with a type-carrier, of a hammer mechanism, a keyboard, connection between the keyboard and the type-carrier for positioning the type, and a universal bar engaged by the keys of the keyboard and operating the hammer mechanism after the type have been positioned.

24. The combination with a keyboard, of a type-carrier and a hammer mechanism traveling relatively to the keyboard, and an oscillatory shaft from which the hammer receives power from the keyboard.

25. The combination with the type-carrier, of an oscillatory arm for moving the type-carrier in the direction of the printing-line, an oscillatory shaft on which the oscillatory arm is mounted, a swinging plate having connection with the oscillatory shaft, and key-levers having portions located at different distances from the swinging plate.

26. The combination with the type-carrier, of an oscillatory arm for moving the type-carrier in the direction of the printing-line, an oscillatory shaft on which the oscillatory arm is mounted, a swinging plate having connection with the oscillatory shaft, and key-levers having portions located at different distances from the swinging plate and curved to pass beneath the plate and hold it in proper position until the key-lever is released.

27. The combination with the type-carrier, a pair of oscillatory shafts carrying means for moving the type-carrier in opposite directions, a pair of swinging plates, each connected with one of the oscillatory shafts, and key-levers divided into two groups, the key-levers of each group having portions located different distances from one of the swinging plates.

28. The combination with the type-carrier, of a pair of swinging plates having connection with the type-carrier to move it in opposite directions, and key-levers having portions located different distances from the swinging plates, to move the plates different distances and curved to permit the portion to pass beneath the plate after it has been moved to the proper position.

29. The combination with the type-carrier, of a pair of swinging plates having connection with the type-carrier to move it in opposite directions, and key-levers having portions located different distances from the swinging plates to move the plates different distances and curved to permit the portion to pass beneath the plate after it has been moved to the proper position, and a hammer mechanism operated by the key-levers after a plate has been moved to the proper position.

30. The combination with a plurality of independently-sliding type-carriers, of means located on opposite sides of the type-carriers for engaging any one of the carriers to move

the same in opposite directions, and opposing springs for moving the type-carrier to normal position.

31. The combination with the hammer mechanism and the key-levers, of a universal bar acted upon by the key-levers, and adjustable means controlling the movement, of the universal bar to vary the force of the blow of the hammer mechanism.

32. The combination of a printing mechanism embodying a plurality of type-carriers, two of which carry ink-pad-engaging members, an ink-pad having a central pathway transverse of the printing-line, and a pathway parallel to the printing-line, and means moving the printing mechanism so that one of the pad-engaging members travels on the central pathway, and means for moving the type-carriers, independently of one another, to cause the other pad-engaging member to travel on the pathway parallel with the printing-line.

33. The combination of a movable inking-pad having a central pathway on its inking-face, recesses or openings at the ends of the central pathway, and lateral pathways leading from one of the openings or recesses, and a printing mechanism having a pair of lugs one of which travels on the central pathway and the other of which moves on the lateral pathway and relative to the first lug.

34. The combination with a printing mechanism movable in the direction of and transverse of the line of printing; of a pair of lugs carried by the printing mechanism, and a plate carrying a pair of ink-pads normally held against the printing mechanism, and provided with a longitudinal pathway between the pads, lateral pathways, and an opening at the juncture of the longitudinal and the lateral pathways, the lugs on the

printing mechanism traveling on the pathways to move the pads away from the printing mechanism, and one of them entering the opening to permit the pads to engage the printing mechanism. 45

35. In a type-writing machine, the combination with the base-plate adapted to support a book, of a roller-platen spaced above the base-plate transverse to the line of writing of the machine. 50

36. The combination of an inking-pad having an opening and a path leading from the opening, and a type-carrier having a lug normally resting in the opening and movable in the path from the opening to move the pad away from the type. 55

37. In a book type-writing machine, the combination with a base-frame adapted to support a book, of a roller-platen spaced above the base-frame, and transverse to the line of writing of the machine, and a printing mechanism positioned above the platen and movable in the direction of the axis of the platen for line-spacing. 60

38. In a book type-writing machine, the combination with a base-frame adapted to support a book, of a roller platen spaced above the base-frame and transverse to the line of writing of the machine, a printing mechanism positioned above the platen and movable in the direction of the axis of the platen for line-spacing, a spring moving said roller in one direction, and an escapement controlling the roller. 65

The foregoing specification signed at the city of New York this 9th day of March, 1905.

AUGUSTO BONTEMPI.
